UNITED STATES PATENT OFFICE

134,539

DESIGN FOR A CANDLE

Lena C. Howard, Brockton, Mass.

Application July 1, 1942, Serial No. 107,382

Term of patent 3½ years

To all whom it may concern:

Be it known that I, Lena C. Howard, a citizen of the United States, residing at Brockton, in the county of Plymouth and State of Massachusetts, have invented a new, original, and ornamental Design for a Candle, of which the following is a specification, reference being had to the accompanying drawing, forming part thereof.

I claim:

The ornamental design for a candle, substantially as shown and described.

LENA C. HOWARD.
